TYPEWRITING AND LIKE MACHINES

Herbert E. Bridgewater, Syracuse, N. Y., assignor
to Remington Rand Inc., Buffalo, N. Y., a corporation of Delaware

Application September 15, 1938, Serial No 230,117

7 Claims. (Cl. 197—33)

My invention relates to typewriting and like machines, and more particularly to improved touch regulating means for varying the operating touch of the type actions to accord with that found most desirable by individual operators.

The main object of my invention, generally stated, is to provide improved means of the character specified which are simple in construction, highly effective in use and convenient in operation.

A further object of my invention is to provide for touch regulation by improved means for varying the tension of a single spring which is stressed at each operation of any type action.

Another object of my invention is to provide touch regulating means of the character specified having improved manually controlled means located at the front portion of the typewriting machine for adjusting the tension of said spring and for indicating the position of adjustment.

A still further object of my invention is to provide manually controlled means for adjusting the touch regulating means for the type actions to any degree of adjustment within the limits thereof and for maintaining such regulating means in any such position to which they may be adjusted.

Another object of my invention is to provide improved means for varying the tension or effective force of a spring means which is stressed to a uniform extent at each operation of any type action during the latter portion of the movement of the associated type bar to the printing point.

To the above and other ends, which will hereinafter appear, my invention consists in the features of construction, arrangement of parts and combinations of devices set forth in the following description and particularly pointed out in the appended claims.

In the accompanying drawings, wherein like reference characters indicate corresponding parts in the different views:

Fig. 1 is a side elevational view with parts omitted of a No. 8 Remington Noiseless portable typewriting machine equipped with the devices of my invention.

Fig. 2 is an enlarged, detail fragmentary top plan view of a portion of the machine shown in Fig. 1, the view showing certain parts broken away and other parts omitted.

Fig. 3 is an enlarged, detail, vertical sectional view of the same taken on line 3—3 of Fig. 2 and viewed in the direction of the arrows at said line.

Fig. 4 is an enlarged, fragmentary side elevational view of a portion of the machine, with parts broken away and showing the devices of my invention in one extreme adjusted position thereof.

Fig. 5 is a view similar to Fig. 4, except that

said parts are shown in another extreme position of adjustment.

Fig. 6 is an enlarged, detail, fragmentary, horizontal sectional view taken on line 6—6 of Fig. 4 and viewed in the direction of the arrows at said line.

Fig. 7 is an enlarged, detail, perspective view of the anchor member shown in Figs. 4, 5 and 6.

I have shown my invention embodied, in the present instance, in a No. 8 Remington Noiseless portable machine in which the features of the present invention may be readily incorporated with but few changes in the existing structure of such machine. However, it is to be understood that my invention is not restricted to embodiment in such machines but may be employed in various other types of typewriting and like machines wherever found available. For example, the devices of my invention in the form herein illustrated may be employed in substantially the same manner in the No. 1, No. 7 and No. 9 Remington portable machines.

I have shown in the accompanying drawings only so much of the usual construction of the No. 8 Remington Noiseless portable machine as is necessary to arrive at an understanding of my invention in its embodiment therein.

The type actions in the present construction may be the same or substantially the same as those shown in the patent to G. G. Going, No. 1,908,140, dated May 9, 1933.

The lower portion of the machine in the present instance is provided with an outer metal shell or housing 10, which extends around the sides and front of the machine. The shell 10 is carried by the usual inner frame which includes side plates 12 (see Figs. 2, 4 and 6) which carry the usual type bar segment and rear cross member not shown. The front end portions of the two side plates 12 are connected to and support a key lever guide comb 14 of the usual construction which is mounted on inwardly turned portions of the side plates 12 by screws 15, as shown in Fig. 2 and Fig. 4.

Each of the type actions of the present machine includes a type bar 17 pivotally mounted at 18 to the usual type bar segment (not shown) which is located between and connects the side plates 12. Each type bar 17 has on the heel thereof a depending semi-circular portion 19 received in a correspondingly shaped recess in a companion actuating slide 20 which is suitably guided for movement fore and aft of the machine. The forward end of each slide 20 is pivotally connected at 21 to a sub-lever 22, which is pivotally mounted at 23 on an upstanding bracket or hanger 24 secured to a supporting member 24a. The forward end of each sub-lever 22 is connected by a pull wire 25 to a companion key lever 26.

The forward end of each of the key levers 26 is

provided with a finger key 27, and the various key levers are of four different lengths in the usual manner to provide a four bank keyboard, as shown in Fig. 1. The rear ends of the key levers forming the first three banks are pivoted upon a transverse fulcrum rod 28 extending between the side plates 12, and the key levers forming the fourth bank are pivoted upon an upper transverse fulcrum rod 29 also extending between the side plates 12.

It will be apparent that a depression of each of the key levers 26 will effect a printing operation of the companion type bar 17 through the pull wire 25, sub-lever 22 and slide 20 associated therewith. A platen 30, shown in Fig. 1, is mounted on the usual case shiftable carriage, not shown. The usual means for effecting noiseless pressure printing operation of each type bar 17 is shown in Fig. 1 as including a toggle arm 32 and toggle link 33. The upper end of each toggle arm 32 is pivotally mounted at 34 in an upper segment (not shown) extending between the side plates 12. The lower end portion of each toggle arm 32 is connected through a link 33 to the upper end portion of the companion type bar 17. An intermediate portion of each toggle arm 32 is connected through part of a momentum accumulator 35 to the upper end of an arm 36 pivotally mounted at 37 in a part of the same lower segment on which the type bars 17 are pivoted.

The toggle members 32 and 33 of each type action operate in the usual manner to decelerate the movement of companion type bar 17 as it approaches the printing position, and the momentum accumulator 35 operates to substantially straighten these toggle members to effect a noiseless pressure imprint of the type 39 on the paper carried by the platen 30. A contractile returning spring 42 is provided between the rearward end of each sub-lever 22 and the associated hanger 24 therefor for returning the companion type action to normal position. A supplemental contractile returning spring 43 is provided between a cross member 44 and each of the toggle sub-levers 36.

In the present machine, the usual universal bar and intermediate connections to the ribbon vibrator are provided for shifting the inking ribbon into and out of the path of the type 39 and also for effecting the longitudinal feed of the ribbon. This universal bar and associated mechanism is actuated by an operation of each of the type actions, and in the present instance includes a universal bar 48 mounted at the forward end of arm 49 carried by a rock shaft 50. The universal-bar rock-shaft 50 is square in cross section and extends transversely of the machine and is pivotally mounted to turn on cone shaped ends of pivot screws 51 extending inward from the two side plates 12. The screws 51 may be threaded into companion tapped openings in the side plates 12 and the position of the screws 51 is retained by companion lock nuts 52. The universal bar 48 extends transversely of the machine beneath all of the key levers 26, and the upper portion of the bar 48 is bent forwardly with slots provided therein between adjacent key levers to provide individual upstanding portions 48a each of which is engaged by a companion key lever 26. These individual contact portions 48a of the universal bar 48 may be bent downwardly or upwardly to provide individual adjustment for the operation of the universal bar for each of the key levers 26.

The mechanism actuated by the universal bar 48 for effecting longitudinal feed of the ribbon and for actuating the ribbon vibrator may, for example, be the same as that shown and described in the patent to G. G. Going No. 1,937,692 dated Dec. 5, 1933. A portion of such mechanism is shown in Fig. 1 as including two upstanding arms 54 and 55 carried by the universal-bar rock-shaft 50, the arm 55 being pivotally connected to a link 56 for operating the ribbon feed mechanism, not shown. The other arm 54 is pivotally connected to a link 57 which extends rearwardly of the machine to effect vertical movement of a ribbon vibrator 58 at each operation of a type action through the usual mechanism which it is not considered necessary to show or to describe in detail in the present instance.

The portion of the machine thus far described is not modified by the incorporation of the devices of my present invention therein and may be of the usual construction ordinarily employed in the No. 8 Remington Noiseless portable machine.

A returning spring is usually provided for the universal bar and the parts controlled thereby, and my invention in the present instance is particularly concerned with the provision of an improved means for readily varying the tension of such returning spring to thereby regulate the operating touch of the type actions to accord with the individual desires of different operators.

Referring particularly to Figs. 2, 4 and 6, it will be seen that a contractile spring 60 is connected at its upper end to an arm 61 attached at 62 to the universal-bar rock-shaft 50 to extend upwardly and rearwardly therefrom. The lower end of the spring 60 is connected to the forward end of an anchor member or arm 64 which is pivotally mounted on a headed shouldered pivot screw 65 threaded into a tapped opening in the right hand side plate 12 and in a bracket 66 which is ordinarily secured to and carried by said side plate 12, as shown in Fig. 6. A slide, member or link 66 is provided at its rear end portion with a longitudinally extending slot 67 which receives the stem portion of the screw 65 to support the member 66 at its rear end for sliding movement fore and aft of the machine. The forward end of the slide 66 is pivotally connected at 68 to the depending arm of a bellcrank 70 which constitutes a manually adjusted touch regulating device, control member or lever. The bellcrank 70 may be mounted to turn around a bushing 71 (see Fig. 3) seated on the body portion of the right hand screw 51 between the associated lock nut 52 and the outer surface of the right hand side plate 12. The forwardly extending arm of the bellcrank 70 is turned upward and terminates in a finger piece 72. As may be seen in Fig. 2, the upwardly extending portion of the bellcrank 70 extends past the inside edge of the bead formed by the inwardly turned portion 10a along the upper edge of the outer shell 10 of the machine. The finger piece 72 overlies the bead 10a along the upper edge of the right hand side of the shell or housing 10 and is thereby positioned for convenient manipulation by the operator at the front of the machine near the keyboard.

The link or slide 66 and the body portion of the anchor member 64 are thus mounted between the right hand side plate 12 and the outer shell member 10 of the machine, as shown in Fig. 6. The forward end of the anchor member 64 is

bent inward at 64^a to pass through an opening 12^a in the lower front corner of the right hand side plate 12 (see Figs. 3 and 6) so that the end of this portion 64^a to which the spring 60 is connected lies beneath the end of the arm 61 of the rock shaft 50.

Means are provided for effecting a pivotal movement of the anchor member 64 by a sliding movement of the member 66. Thus, a headed pin 75 is riveted at a reduced diameter portion thereof to the slide member 66, and the stem of this pin 75 is received in a diagonally disposed cam slot or elongated opening 76 provided in the central portion of the anchor arm 64. This pin and slot connection provides in effect a cam operating connection whereby a fore and aft sliding movement of the member 66 effects a pivotal movement of the arm 64 about the pivot screw 65.

It will now be apparent that an operator can readily manually adjust the control lever or bell-crank 70 by the finger piece 72 at the front portion of the machine to effect a sliding movement of the member 66 which in turn will cause a pivotal adjustment of the anchor member 64 and thereby increase or decrease the tension of the spring 60. However, the construction and arrangement of the parts are such that the reactive force of the spring 60 in any adjustment of the parts of the touch regulating means will not displace such parts from the positions to which they have been adjusted. Thus it will be seen that the greatest component of the reactive force of the spring 60 is exerted to turn the member 66 upward around the pivot 65 as a center, but that such force is exerted longitudinally against the depending arm of the control lever 70 and against the fixed pivot of said lever whatever may be the adjustment of the lever. The reactive force of the spring 60 to displace the parts of the touch regulating means from their adjusted positions is therefore effectively resisted without the necessity of employing any special detent mechanism.

It will be clear that the range of adjustment of the present mechanism will be determined by the length of the slots 67 and 76, and the engagement of the end walls of the slot 67 with the body portion of the pivot screw 65 provides an effective stop for limiting the two extreme adjusted positions of the control lever 70 and the parts controlled thereby. Inasmuch as the pin and slot connection between the members 64 and 66 does not permit the tension of the spring 60 to cause a movement of the control or adjusting lever 70 and the parts controlled thereby, it will be clear that any degree of adjustment of the tension of the spring 60 within the limits of movement of the touch control mechanism may be effected as the control lever 70 and parts operated thereby will be retained in any position to which they are moved by the operator.

Means are also provided in the present instance for indicating the position of adjustment of the touch regulating mechanism. Such indicating means are provided in the present instance by the indices L and H and intermediate scale or division lines 78 suitably marked on the upper edge portion 10^a of the shell 10 of the frame 70 of the machine, as shown in Fig. 2. These indices are positioned beneath the finger piece 72 and cooperate therewith to indicate to the operator the existing position of adjustment of the touch regulating mechanism. The indicium L indicates that the finger piece 72 is to be moved rear-

wardly of the machine toward an extreme position illustrated in Fig. 5 to afford a relatively light operating touch, while the indicium H indicates that the finger piece is to be moved forwardly of the machine toward an extreme position shown in Fig. 4 to obtain a relatively heavy operating touch. The scale division lines 78 will of course indicate various intermediate degrees of touch between the lightest and the heaviest which can be afforded by the range of adjustment of the regulating means.

Referring to Figs. 1 and 4, it may be seen that certain of the key levers 26 have a relatively different extent of pivotal operating movement before the shoulder portion 26^a thereof engages a resilient stop strip 80 mounted at the lower end of the guide comb 14. Thus, the key levers 26 which have keys 27 forming the first or lower transverse row or bank of keys have the shortest extent of pivotal movement while the second, third and fourth banks successively increase slightly in their extent of pivotal movement. In order that the four groups of key levers having these relatively different extents of travel may all afford a uniform actuating movement of the universal bar mechanism, the portions 26^b of these four groups of key levers which overlie the universal bar 48 are staggered in different vertically spaced relationship to provide different extents of lost motion between the key levers and the universal bar. In this manner the universal bar returning spring 60 will be stressed to a uniform extent irrespective of the variation in the dip or pivotal movement of the various key levers 26.

From the above it will be clear that the extent of lost motion between the key levers and the universal bar is relatively different in the four groups of key levers associated with the different banks of keys, and accordingly a change in the tension or effective force of the spring 60 will be ineffective to alter the touch throughout slightly different portions of the initial movement of these different groups of keys. Therefore, during such initial movement of each type action 45 it is necessary to overcome the force of the returning springs 42 and 43 only, thereby affording a light initial touch on the keys irrespective of the adjustment of the tension of the spring 60. The tension or effective force of the spring 60 is not exerted against each type action until after the parts thereof are set in motion when the resistance of such force is felt less upon the keys. The spring 60 then provides a uniform resistance throughout a fixed extent of the latter portion of the movement of the actuated type action. Accordingly, a change in the tension or effective force of the spring 60 will uniformly alter the operating touch during the latter portion of the movement of all of the type 60 actions. Inasmuch as the returning spring 60 for the universal bar mechanism aids materially in the initial portion of the return movement of each type action from the printing position, it will be clear that the tension of the spring 60 in the present instance will be equally effective on all of the type actions during this initial portion of the return movement thereof.

From the aspect of effecting a snappy quick return of each type bar from its printing position, 70 thereby preventing interference or collision between the various type bars near the printing point, or within the danger zone, it is very desirable that the universal bar returning spring 60 act uniformly on all of the type actions dur- 75

ing the latter portion of the travel of the type bars to and from the printing point to afford a uniform fast operation of all of the type bars in the zone where the danger of interference or 5 collision is the greatest.

It will be seen that I have thus provided a very simple and yet highly effective touch regulating means which may be readily adjusted to simultaneously regulate the operating touch of 10 all of the type actions to accord with the individual desires of different operators. I have also provided a convenient indicating means whereby the operator may readily determine the different quality of touch to be afforded by the different 15 positions of the control or adjusting member.

A particular feature of the present invention is in the provision of a highly effective touch regulating means by varying the tension or effective force of the spring means such as is ordinarily 20 employed to return the universal bar mechanism to normal position, inasmuch as such spring means is of course stressed at each operation of any type action and accordingly any change in the tension of such spring means 25 simultaneously affords a variation in the operating touch of all of the type actions.

A further feature of the present invention is the provision of an adjusting means for spring means stressed by the operation of the type actions 30 wherein there are no defined increments or fixed positions of adjustment and which thereby affords any degree of infinitely fine adjustment of the operating touch within the limits thereof.

Although in the present instance the touch regulating mechanism of the present invention has been shown applied to the returning spring for a universal bar mechanism employed for effecting the usual feed movement of a ribbon 35 and the actuation of the ribbon vibrator, it will be clear that the present mechanism could be employed in a similar manner to vary the tension of the returning spring for a universal bar ordinarily provided for other purposes such for 40 example, as for operating the usual carriage escapement mechanism. It will also be clear that from certain aspects of my invention the present touch regulating mechanism could be applied to vary the tension of a returning spring for a universal bar operated by different parts of the type 45 action other than the key levers, such for example as the sub-levers or the type bars. In other instances a universal bar may be provided solely for tensioning purposes without being connected to operate or control other elements of the 50 machine.

Various changes may be made in the construction, and certain features thereof may be employed without others, without departing from 55 my invention as it is defined in the accompanying claims.

What I claim as new and desire to secure by Letters Patent is:

1. In a typewriting machine, the combination 60 of type actions, a universal bar actuated thereby and operatively connected to actuate a part of the machine, a single spring for returning said universal bar to normal position, and manually controlled touch regulating means for varying the tension of said spring, said touch regulating 65 means comprising a pivoted member to which one end of said spring is anchored, a hand controlled pivoted member, a slide that is actuated 70

thereby, and cam connections between said slide and said first named pivoted member.

2. In a typewriting machine, the combination 5 of type actions, a universal bar operated thereby, a single spring which is stressed at each operation of said universal bar, a pivoted anchor member to which one end of said spring is connected, a slide, operative connections between said slide and anchor member to effect a pivotal movement of the latter by a sliding movement of the slide, and a control lever having a finger piece at the front portion of the machine and operatively connected to said slide to adjust it.

3. In a typewriting machine, the combination 15 of type actions, a universal bar actuated thereby, a spring for returning said universal bar to normal position and touch regulating means therefor comprising a pivoted anchor member to which one end of said spring is connected, a slide, cam 20 connections between said slide and anchor member to effect a pivotal movement of the latter by a sliding movement of the slide, a control lever having a finger piece at the front portion of the machine and operatively connected to said slide to adjust it, and indices for indicating the position of adjustment of said control lever.

4. In a typewriting machine, the combination 30 of type actions, a universal bar operated thereby, a single spring which is stressed at each operation of said universal bar, a pivoted anchor member having an inclined slot therein and to which one end of said spring is connected, a slide having a pin received in said inclined slot, and a manually adjusted control lever operatively 35 connected to said slide.

5. In a typewriting machine, the combination 40 of type actions, a universal bar actuated thereby, a spring for returning said universal bar to normal position, and touch regulating means for varying the touch on the printing keys comprising a pivoted arm having an inclined slot therein and to which one end of said spring is anchored, a link mounted at one end to receive a sliding movement and provided with a pin received 45 in said inclined slot, a control lever having a finger piece near one side of the frame of the machine at the keyboard, said control lever being pivoted to the opposite end of said link, and indices with which said control lever coacts to indicate the position of adjustment thereof.

6. In a typewriting machine, the combination 50 of a plurality of type actions, a universal bar operated by each of said type actions, a spring for returning said universal bar to normal position, a movable anchor to which one end of said spring is connected, an adjusting member mounted for sliding movement, and cam operating means for moving said anchor by movement of said adjusting member.

7. In a typewriting machine, the combination 55 of a plurality of type actions, a universal bar operated by each of said type actions, a spring for returning said universal bar to normal position, a movable anchor to which one end of said spring is connected, an adjusting member mounted for sliding movement, cam means on said anchor inclined with respect to the direction of movement of said adjusting member, and means on said adjusting member coacting with said cam means to cause movement of the anchor by movement of said adjusting member.

HERBERT E. BRIDGWATER.
